US00D767631S

(12) United States Design Patent (10) Patent No.: US D767,631 S
(45) Date of Patent: * Sep. 27, 2016

(54) DISPLAY SCREEN OR PORTION THEREOF WITH ICON

(71) Applicant: Samsung Electronics Co., Ltd., Suwon-si, Gyeonggi-do (KR)

(72) Inventors: Serrah Lim, Bucheon-si (KR); Subin Jin, Seoul (KR)

(73) Assignee: SAMSUNG ELECTRONICS CO., LTD. (KR)

() Term: 15 Years

(21) Appl. No.: 29/537,485

(22) Filed: Aug. 26, 2015

(51) LOC (10) Cl. 14-04

(52) U.S. Cl.

USPC D14/492

(58) Field of Classification Search

USPC D14/485-495

CPC G06F 3/041; G06F 3/04817

(57) CLAIM

The ornamental design for a display screen or portion thereof with icon, as shown and described.

DESCRIPTION

The FIGURE is a front view of a display screen or portion thereof with icon, showing our new design.

The broken lines illustrating portions of the display screen or portion thereof with icon form no part of the claimed design. The dot-dash lines in the figure represent a boundary line and form no part of the claimed design.
